UNITED STATES PATENT OFFICE.

ELIHU THOMSON AND EDWIN WILBUR RICE, OF LYNN, MASSACHUSETTS,
ASSIGNORS TO THE THOMSON-HOUSTON ELECTRIC COMPANY, OF CON-
NECTICUT.

ELECTRIC-ARC LAMP.

SPECIFICATION forming part of Letters Patent No. 440,663, dated November 18, 1890.

Application filed January 3, 1884. Serial No. 116,331. (No model.)

To all whom it may concern:

Be it known that we, ELIHU THOMSON and EDWIN WILBUR RICE, citizens of the United States, and residents of Lynn, in the county of Essex and State of Massachusetts, have invented certain new and useful Improvements in Electric-Arc Lamps, of which the following is a specification.

Our invention relates to electric-arc lamps, and is designed especially to simplify the construction and operation of arc lamps and at the same time to permit the ordinary feed-regulating or carbon-adjusting operations to be controlled by the current in a high-resistance derived circuit only, acting in opposition to a retracting spring or weight, instead of making such operations dependent upon the differential action of main and derived circuit coils or magnets, respectively, in circuit with the carbons and in a high-resistance derived circuit around them.

Our present invention relates to certain improved details in electric lamps of the form in which are combined a feed-regulating armature or lever from which the carbon or other electrode is suspended or supported, a derived-circuit coil of high-resistance acting on said lever in opposition to a suitable retractor to control the position of the electrode, a starting or assisting coil or circuit through which current flows at the start to bring the said carbon-supporting lever into properly-acting position, and a switching device for switching out said coil or circuit directly dependent upon the establishment of circuit through the carbon or electrodes.

Our invention consists in certain combinations and arrangements of devices designed to simplify and improve the operation of the lamp.

The invention will be described in general terms in connection with the accompanying drawings, and will then be more particularly pointed out in the claims.

In carrying out our invention we prefer to use the electro-magnetic effects of the current in the starting-circuit to produce the desired operation, but do not limit ourselves in this respect, as we may use any of the motor

effects of a current and may therefore produce 50 the desired results by means of a thermostat or other device actuated or energized directly or indirectly by the heating effects of the current flowing through an artificial resistance in the starting-circuit.

In the accompanying drawings, Figure 1 is an elevation of an electric lamp containing our invention. Fig. 2 is a plan of the same. Fig. 3 shows a modified disposition of the coils. Figs. 4, 5, and 6 show other arrangements for carrying out the invention. Fig. 7 shows how the heating effects of a current in the starting-circuit may be utilized for the purposes of our invention.

Referring to Fig. 1, E E' indicate, respectively, the positive and negative carbons of an electric-arc lamp, and R the carbon rod or carrier supporting the positive carbon and engaged by any suitable feed-regulating mechanism. That here shown consists of an ordinary clamp or clutch constructed according to the invention of E. Thomson, and composed of a clamp body or guide C, through which the rod R may move, a pivoted clutch or jaw T, pivoted on C and normally engaged with the rod by a spring Z, so as to prevent the rod from moving downward through the clutch, and a releasing-stop F, with which an arm of T engages when the clutch is lowered sufficiently, so as to permit the rod and positive carbon to move downward. When the clutch is raised bodily by any means away from the stop, the carbon is raised with it. The clutch may be replaced by any mechanism which when moved in one direction will raise the carbon and when moved in the other will release it.

L indicates a feed-regulating armature-lever, which serves to impart movement to the clutch, or feed-regulating mechanism, in any 90 proper manner—as, for instance, by a link D.

S indicates the retractor for the armature, which retractor, when unopposed, lifts the clutch, and with it the upper carbon, while B indicates the armature of a derived-circuit 95 magnet of high resistance, whose coils are indicated at K, and which acts in opposition to the retractor.

The armature is perforated, and the pole of the magnet is conoidal or paraboloidal in form, as described and shown in a prior patent granted to E. Thomson, so that with the same 5 strength of current the pull upon the lever L will be the same in all positions of the armature. The coil K is in the usual derived circuit around the carbons, which circuit is indicated by the numeral 5.

- 10 G indicates a starting-coil, the object of which is, when current is turned on, to pull down the lever L and cause the carbons to come together. It is preferably of low resistance and wound upon the same core with coils 15 K, so that at the start it will strongly magnetize the core acting on armature B.

Coil G is in the present instance in a branch around the carbons, which branch is indicated by the numeral 6 and includes the contact- 20 points b of a switch or circuit-controller W, upon which a retractor Z² acts, so as to tend to keep the contacts b closed.

As will be observed, the coils K are in a circuit around both G and contacts b, with the 25 double effect that the opening of contacts b can only affect the circuit of G, and that the spark of rupture, if any be produced, will be taken up and absorbed by the coils and core of K. The absorbing or neutralizing action 30 is also largely increased by the placing of the coils G and K upon the same core, which coils are then respectively related to one another as the primary and secondary of an induction, coil, whose secondary current will flow in local 35 circuit with contacts b and will neutralize the spark of rupture. The branch 6 is, as obvious, a branch around the carbons.

The carbon-circuit at some point between X and Y contains the low-resistance magnet 40 M, which when energized acts upon its armature N, attached to circuit closer and controller W, and if the contacts b are at such time closed will open them and hold them open, so as to open the circuit of coils G and 45 render the latter inactive. Magnet M obviously acts only when the current flows in the carbon-circuit with E E'. At other times, as when the lamp is out of action, the circuit of coils G is closed by the spring Z². The 50 magnet G K may obviously be a single-core magnet or a double or horseshoe magnet, as indicated in Fig. 2, each leg of said magnet being wound with two coils G and K, or one leg carrying one coil, as G, and the other leg 55 the other coil, as K. When the lamp is out of action or no current passing, the parts are in the position shown in Fig. 1, the lever L being retracted to an extreme position, so as to raise the clutch and hold the carbons separated. The circuit of coil G is closed through 60 contacts b by the action of spring Z².

The operation is as follows: When the current is turned onto the circuit containing the lamp, the current from X, finding no circuit 65 at E E', because the carbons are separated at the start, passes through the coil G, through contacts b, and out at Y. The magnet G K

then attracts its armature B B, lowering and releasing the feeding mechanism and dropping the carbons into contact. At this moment the magnet M is energized by the current passing through the carbons and attracts its armature N, opening the circuit of coil G at b against the action of retractor Z². The coil G is now out of circuit and ineffective, 75 while the contact b is kept open by the passage of current at E E'. An arc is now formed by the retractile force of S, lifting and locking the clutch C and raising R until restrained by the increased force of derived- 80 circuit coil K upon B B, due to the increase of resistance between E E'. The lamp now acts to feed by the sole agency of K. The stoppage of current in the lamp restores the parts to their original positions. 85

It is not necessary that G K be wound upon the same magnet or the same core; but they are preferably so wound for simplicity. Two magnets may be used to replace the combined magnet G K, and two armatures B B' attached to L, as seen in Fig. 3. Many other equivalent arrangements are possible. Instead of pulling L down, the action of G may be to depress the lever L indirectly by slackening temporarily the spring S. Such a construction is indicated in Fig. 4, where the retractor S, instead of being attached to a fixed support, is attached to the armature-lever L' of the starting-magnet G. The retractor S' for L' is strong enough to overcome the tension of S 90 and to give to the latter the normal tension required in the ordinary operation of L. When, however, the magnet G is energized, the armature L is drawn up, thus slackening the tension of S, so that the current flowing 95 in magnet-coil K at the start will be sufficient to pull down lever L and start the lamp; or the coil G may act to lower the clutch C independently of a descent of L. This is shown in Fig. 5, where the lever L carries the magnet G, whose armature-lever L' lowers C when attracted against the force of the spring S'. After contact at E E', G is open-circuited, as before, and, releasing its armature L', an arc is formed at E E', the 100 regulation of which is afterward effected by variations of K alone acting on the armature B B upon L and against the spring S. If desired, the coil or magnet G may at the start lower both the magnet K and its armature, as 105 indicated in Fig. 6, where K is shown as mounted in an armature-lever L' for G, which at the start lowers K and also slackens the retractor S for L. When G becomes inactive, retractor S' raises K, and at the same time 110 gives to S the proper tension. If desired, the coil G may act as an electro-thermo-motor-device through the increase of temperature in it due to the passage of current through it. This may be accomplished by the device 115 shown in Fig. 7, where the coil G is shown inclosed in a cylinder containing air or other fluid expansible by heat, and the piston of said cylinder is arranged to exert a pressure

120

135

upon the lever L, so as to lower the same and start the lamp, when the fluid expands by heat developed in G acting as a resistance. A compound bar might be substituted for the 5 fluid.

It is to be understood that lamps containing gear-trains may be operated in accordance with our invention, provided only that their mechanism can be put under the control of 10 an armature B B or equivalent axial core.

What we claim as our invention is—

1. The combination, in an electric lamp, of a stationary high-resistance derived-circuit magnet, an armature therefor, a lever carrying said armature and supporting the electrode and actuated in opposite directions by 15 said derived-circuit magnet and a suitable retractor, a starting or assisting coil wound on the same fixed core with the derived-circuit 20 coils and placed in an auxiliary or independent branch around the carbons closed when the circuit through the carbons is broken, and means for breaking said auxiliary branch placed in a circuit closed through the carbons 25 when they come together.

2. The combination, in an electric lamp, of a high-resistance derived-circuit magnet, a carbon-supporting and feed-regulating mechanism actuated by said magnet in opposition 30 to a suitable retractor, a stationary auxiliary or starting coil upon the same core with the high-resistance coil, and means for cutting out or rendering said auxiliary or starting coil inactive placed in a circuit completed through 35 the carbons.

3. The combination, in an electric lamp, of a fixed high-resistance derived-circuit magnet having a conical pole, a perforated armature, feed-regulating mechanism actuated 40 thereby in opposition to a suitable retractor in a direction to lower the carbon and at the same time cause a feed upon an increase in the

length of arc, a fixed auxiliary starting or assisting coil acting on the armature-lever in the same direction as the derived-circuit coil and 45 placed in a circuit closed when the lamp is out of action, and means for cutting out or rendering said coil inactive placed in a circuit closed only through the carbons.

4. The combination, in an electric-arc lamp, 50 of a derived-circuit magnet, a feed-regulating mechanism engaging with and normally supporting the carbon-carrier, a support for said mechanism acted upon by said magnet in a direction to lower the carbon, a retractor 55 tending to lift the support, and three independent branches or circuits, one including the derived-circuit magnet, another a starting coil or circuit, and the third including the carbons and a switching-magnet, by which 60 the starting coil or circuit is switched out of operation on the establishment of circuit through the carbons.

5. The combination, in an electric-arc lamp, 65 of a high-resistance derived-circuit magnet, an armature lever therefor supporting the carbon-electrodes and actuated in opposite directions by said magnet and by a suitable retractor, a starting coil or circuit on the core of said derived-circuit magnet, a circuit-controller for throwing said starting-coil out of 70 action, and a magnet in the carbon branch and in a circuit independent of the derived-circuit magnet for operating said circuit-controller.

Signed at Lynn, in the county of Essex and State of Massachusetts, this 28th day of December, A. D. 1883.
